UNITED STATES PATENT OFFICE.

WILLIAM H. SPENCER, OF BROOKLYN, NEW YORK, ASSIGNOR TO GEORGE FRINK SPENCER,
OF NEWARK, NEW JERSEY.

SUPPORTING-SOCKET FOR REFLECTORS.

No. 927,818.

Specification of Letters Patent. Patented July 13, 1909.

Application filed May 20, 1908. Serial No. 433,869.

To all whom it may concern:

Be it known that I, WILLIAM H. SPENCER, a citizen of the United States, residing at Brooklyn, in the county of Kings and State of New York, have invented certain new and useful Improvements in Supporting-Sockets for Reflectors; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in reflectors; and, the invention has reference, more particularly, to a novel device for adjustably mounting the reflector upon the end-portion of a supporting rod, stem, bracket, or other means of support, said device comprising a pair of pivotally connected and tubular socket-members or elements through which the wires for conducting the electricity to the lamp or lamps within the reflector are drawn.

My present invention, therefore, has for its principal object to provide a novel supporting socket for reflectors, and a novel means of attaching the socket to the reflector-body or shell, with a view of providing a hollow or tubular socket which can be easily and quickly attached to a supporting rod, stem, bracket, or other means of support, such as the usual moldings in which electric conductors or wires are carried from place to place, said supporting socket being simple in its general construction, being readily secured to the body or shell of the reflector, and the interior construction of the tubular or hollow parts of the supporting socket being such, that during the installation of the wiring system, as well as in the case of making any necessary repairs, the conducting wires can be easily and quickly drawn through the parts of the supporting socket and into the reflector-body without any danger or possibility of chafing or otherwise injuring and destroying the usefulness of the insulation upon the wires.

The invention has for its further object to provide a novel two-part supporting socket for reflectors, the two members of which are pivotally connected, for the angular adjustment of the reflector-body or shell, and the

pivotal arrangement of said members being such, that, in the case of having to make repairs to the wires or to the reflector-body, the said socket-members can be readily separated without having to disconnect the one 60 socket-member from the usual supporting rod, stem, bracket, or conductor-molding, and without being compelled to remove the other socket-member from the reflector-body or shell, as is at present ordinarily the case. 65

Other objects of this invention not at this time more particularly mentioned will be clearly understood from the following detailed description.

With the various objects of my present invention in view, the said invention consists, primarily, in the novel supporting socket for reflectors hereinafter set forth; and, the invention consists, furthermore, in the various novel arrangements and combinations 75 of device and parts, as well as in the details of the construction of the same, all of which will be more fully described in the following specification, and then finally embodied in the clauses of the claim which are appended to said specification and which form an essential part of the same.

The invention is clearly illustrated in the accompanying drawings, in which:—

Figure 1 is an elevation of one form of 85 reflector or shade provided with a supporting socket embodying the principles of my present invention; Fig. 2 is an end elevation of the devices shown in said Fig. 1; and Fig. 3 is a transverse vertical section taken 90 on line 3—3 in said Fig. 1. Fig. 4 is a face view of a portion of the inner surface of the reflector, showing in end elevation a portion of the reflector-supporting socket extending into the reflector-body, and said 95 view also showing in connection with the said parts, a means for securing the ends of the adjacent reflector elements or glasses, on opposite sides of the said end-portion of the reflector-socket, to the inner surface of 100 the said reflector-body or shell. Fig. 5 is a horizontal sectional representation of the supporting socket, said section being taken directly through the means of pivotal connection of the two socket members, looking 105 in a downward direction; and Fig. 6 is a plan view of a blank of the main supporting or retaining plate of the lower member of the supporting socket, before its retaining or holding portions are bent into shape, 110

and before being secured upon the outer surface of the reflector-body or shell. Fig. 7 is a longitudinal sectional representation of a portion of the metallic reflector-body or shell and reflector-elements or glasses, said view showing in connection therewith and in front elevation the supporting-socket embodying the principles of my present invention, said view being made on an enlarged scale; and Fig. 8 is a longitudinal vertical section of the said parts, showing in connection with said view, and in side elevation, one form of double-lamp receiving socket attached to the end-portion of a tubular wire-conveying member suitably connected with the one member of the supporting socket and extending into the body of said reflector. Fig. 9 is a transverse vertical section taken on line 9—9 in said Fig. 7. Fig. 10 is a front elevation of a reflector-supporting socket of a slightly modified construction, but still embodying the principles of the present invention, showing the use of the socket with a wall or ceiling-molding in which the usual electric wires or conductors are conveyed from place to place; and Fig. 11 is a transverse section of the parts, said section being taken on line 11—11 in said Fig. 10.

Similar characters of reference are employed in all of the above described views, to indicate corresponding parts.

Referring now to the said drawings, the reference-character 1 indicates any suitably formed and suitably constructed reflector, the same being usually made from sheet-metal shaped into any suitable cross-sectional conformation. The sheet-metal reflector-body or shell is provided upon its inner surface-portions with variously disposed holding prongs or tongues 2 which are bent over the marginal edges of suitably disposed and suitably shaped reflector-elements or glasses, as 3. In the present instance, the reflector-body or shell is of an angular cross-section, formed by any suitable number of angularly disposed and connected portions or elements 4. Connected with one of these portions or elements 4 is the supporting socket embodying the principles of the present invention.

Referring now more particularly to Figs. 1 to 9 inclusive, in which I have shown a supporting socket which is adapted for the attachment of the reflector-body or shell to a hollow rod, stem, bracket, or other similar support, for conveying the electric light wires to the lamp or lamps of the reflector, the said socket or fixture consists essentially of two socket-members 5 and 6 of the general construction to be presently described. The socket-member 5, which is the one which is to be directly secured to one of the flat portions or elements 4 of the reflector-body or shell, comprises a flat plate-

like member 7 of sheet-metal formed with a centrally disposed oval hole or opening 8 and oppositely disposed retaining or holding tongues 9 extending from the marginal edge-portions of said plate-like member. 70 In its opposite end-portions 10, the said plate 7 is provided with screw or bolt-receiving holes or perforations 11 for the reception of suitable screws 12 which extend through the reflector-body or shell, from the interior thereof and through the perforations or holes 11, the parts being secured in their assembled relations by means of said screws or bolts and the nuts 13 arranged upon the screw-threaded shanks of 80 the screws or bolts. Suitably arranged upon the said plate 7 is a pivot-member 14, also made of sheet-metal, and formed with a centrally disposed oval opening 16 and a pair of upwardly extending and perforated ears or lugs 15. The said pivot-member 14 is placed directly upon the said plate 7 in such a manner that its opening or hole 16 will register with the opening or hole 8 in the plate 7, and the said 90 marginal retaining or holding tongues 9 are bent upwardly and over the opposite marginal edges of the main body of said pivot-member 14, so that the latter will be tightly and rigidly connected with said plate 7, as 95 will be clearly evident from an inspection of the several figures of the drawings. Extending through the registering oval holes or perforations of the said plate 7 and the said pivot-member 14 is a short piece of 100 piping 17, the same being secured in its operative position by means of the beaded and preferably flattened end-portion 18, and held against turning in said oval holes by said flattened part 18. The said piece 105 of piping or tubing 17 also extends through a suitably formed opening 19 in the part or element 4 of the reflector body or shell, and through an opening 21 in a plate 20 which is suitably secured upon the inner 110 face of said portion or member 4 and has its ends bent in a manner to form holding or clamping tongues 22 which engage with the ends of the respective reflector-sections or glasses located on opposite sides of said tube or pipe 17, in the manner clearly illustrated in Figs. 7, 8 and 9 of the drawings. Upon its lower end portion the said tube or pipe 17 is made with a screw-thread 23, forming a suitable nipple upon which may be 120 screwed the internally screw-threaded fastening member or socket 25 of any suitably constructed light-receiving socket 24.

The previously mentioned socket-member 6 comprises a tubular body-portion 26 which 125 is formed with an external screw-thread 27, and with a pair of downwardly extending ears 28. Each ear 28 is provided with a screw-threaded hole or perforation 29, and when the said ears or lugs 28 are arranged 130

between the ears or lugs 15, in the manner shown, the said screw-threaded holes or openings 31 will register with the perforations or holes 30 in said ears or lugs 15. Pin-ties or screws 29 are inserted through the said holes 30 and screwed directly into the said screw-threaded holes 29, whereby the two socket members 5 and 6 are pivotally or oscillatorily connected so as to permit of the proper angular adjustment of the said members, and in consequence thereof of the reflector or shade. To secure the said socket-members in their adjusted position all that is necessary is to cause a binding action of the said sheet-metal ears 15, the same being capable of a certain amount of spring-like action, against the rigid ears 28, by tightening up the said screws 29, as will be clearly evident. The purpose of the screw-threaded portion 27 of the socket-member 6 is to enable the attachment of the supporting device to the end-portion of a tubular rod or stem 32, or other suitable supporting means, through which the conducting wires 33 and 34 are conveyed into and through the tubular portion of the socket-member 6 and then into and through the pipe 17 to the lamp-receiving socket mounted upon the lower end-portion of the said tube or pipe 17.

30. That the various parts hereinabove described may be properly secured in their operative positions, the central openings in the plates 7 and the body of the pivot-member 14 are preferably made of an elongated 35 or elliptical shape, as has been stated, the upper end of the said tube or pipe 17 being suitably flattened upon both sides, substantially as shown in the several figures of the drawings, so as to correspond to the shape of said elongated or elliptical opening, so as to prevent turning when fitted therein, and the edge of the said pipe or tube is beaded over to secure the parts in place, and so as to leave no sharp marginal edges for the chafing or cutting of the insulation upon the conducting wires, when the latter are being pulled through the pivotally connected parts of the supporting socket or fixture for the attachment to the lamp or lamps within the reflector body.

When the reflector or shade is to be attached directly to the usual wall or ceiling molding, I employ a slightly modified form of socket-member 35 in lieu of the socket-member 6, as clearly indicated in the modification shown in Figs. 10 and 11 of the drawings. In these figures of the drawings, the reference-character 36 indicates the usual wall or ceiling molding formed with the grooves or ducts 37 for the reception therein of the wires 38 and 39. The usual covering for the said molding is indicated by the reference-character 40, and the same is provided at the desired points with the holes or perforations 41 through which the conduct-

ing wires are passed into and through the socket-member 35, as clearly indicated in Fig. 11 of the drawings. The said socket-member 35 consists essentially of a chambered element or box-like member 42 which is provided in its upper surface 43 with an opening 44, and at its ends is made with suitably formed perforated lugs or ears 45 for the reception of screws 46 by means of which the said socket-member 35 can be secured directly to the said molding, as will be clearly understood from an inspection of said figures of the drawings. The said box-like member or element 42 is also provided with a pair of rigidly formed ears or lugs 47 which are made with screw-threaded holes in the manner of the holes formed in the previously mentioned ears or lugs 28, whereby the said socket-member 35 can be pivotally connected with the socket-member 5 of the reflector-body or shell for the proper angular adjustment of the said parts, in substantially the same manner as hereinabove described.

Thus it will be clearly seen from the foregoing description of my present invention that I have provided a supporting socket for reflectors, the parts of which permit of the various angular adjustments of the reflector with relation to a supporting rod, stem, bracket, molding, or the like; and, furthermore, by means of the pivoted arrangement of the two socket-members, the same being separably connected by means of the pivot screws, the said members can be quickly and easily separated without disturbing the position of either member upon the reflector body or upon the end of the supporting rod, stem, bracket, or molding.

I am fully aware that some changes may be made in the various arrangements and combinations of the devices and parts, as well as in the details of the construction of the same, without departing from the scope of my present invention as set forth in the foregoing specification and as defined in the appended claims. Hence I do not confine my invention to the exact arrangements and combinations of the devices and parts described in said specification, nor do I confine myself to the exact details of the construction of the said parts as illustrated in the accompanying drawings.

I claim:

1. A supporting socket for reflectors comprising a flat plate-like member provided with means for attaching it to a reflector-body and having marginal clamping lips, said plate-like body being provided with a hole, a pivot-member upon said flat plate-like member, said clamping lips being in clamped holding engagement with the marginal edge-portions of said pivot-member, said pivot-member being provided with a hole registering with the hole in said plate-

like member, and a tubular socket-member pivotally connected with said pivot-member, substantially as and for the purposes set forth.

5. 2. A supporting socket for reflectors comprising a flat plate-like member provided with means for attaching it to a reflector-body and having marginal clamping lips, said plate-like body being provided with a 10 hole, a pivot-member upon said flat plate-like member, said clamping lips being in clamped holding engagement with the marginal edge-portions of said pivot-member, said pivot-member being provided with a 15 hole registering with the hole in said plate-like member, a tubing extending through the holes in said pivot-member and said plate-like member, said tube having its one end-portion secured to said pivot-member, and 20 its other end being provided with means for the mounting thereon of a lamp-receiving socket, substantially as and for the purposes set forth.

3. A supporting socket for reflectors comprising a flat plate-like member provided 25 with means for attaching it to a reflector-body and having marginal clamping lips, said plate-like body being provided with a hole, a pivot-member upon said flat plate- 30 like member, said clamping lips being in clamped holding engagement with the marginal edge-portions of said pivot-member, said pivot-member being provided with a hole registering with the hole in said plate- 35 like member, and a tubing extending through the holes in said pivot-member and said plate-like member, said tubing being formed with an annular bead for securing said tubing to said pivot-member.

4. A supporting socket for reflectors comprising a flat plate-like member provided with means for attaching it to a reflector-body and having marginal clamping lips, 40 said plate-like body being provided with an oval hole, a pivot-member upon said flat 45 plate-like member, said clamping lips being in clamped holding engagement with the marginal edge-portions of said pivot-member, said pivot-member being provided with an oval hole registering with the hole in said 50 plate-like member, and a tubing having a flattened end-portion arranged in said oval holes to prevent turning, and means for securing said end-portion of the tubing to 55 said pivot-member.

5. A supporting socket for reflectors comprising a flat plate-like member provided with means for attaching it to a reflector-body and having marginal clamping lips, 60 said plate-like body being provided with an oval hole, a pivot-member upon said flat plate-like member, said clamping lips being in clamped holding engagement with the marginal edge-portions of said pivot-member, 65 said pivot-member being provided with an oval hole registering with the hole in said plate-like member, and a tubing having a flattened end-portion arranged in said oval holes to prevent turning, said tubing being 70 formed with an annular bead for securing said tubing to said pivot-member.

In testimony, that I claim the invention set forth above I have hereunto set my hand this 18th day of May, 1908.

WILLIAM H. SPENCER.
